CARBURETOR

James C. Richardson, Naugatuck, Conn.

Application May 8, 1950, Serial No. 160,645

8 Claims. (Cl. 261—51)

1

This invention relates to fuel-air mixing devices or carburetors for internal combustion engines, and particularly to carburetors of the type intended to provide a thorough intermixture between a volatile fluid fuel, such as gasoline, and

5 air.

The art of carburetor building has seen progress in many directions, carburetors having been developed which attempt to take care of a large number of varying conditions, and many of which are reasonably successful. Many if not all of these advanced carburetors, however, are totally unsuited to ordinary use, for example on the usual passenger motor car. They are not only excessively costly initially, but they also require 15 unusual skill for their maintenance which would make their upkeep too precarious and too costly for ordinary use.

The fact that development and improvement of carburetors for specialized purposes has apparently required multiplication of moving parts, controls, and adjustments, seems to have diverted the investigation relating to the improvement of ordinary commercial gasoline engine carburetors such as are used on automobiles from its proper channels. One of the main considerations in the design of a carburetor for wide public use is simplicity and freedom, insofar as possible, from delicate moving parts and adjustments, with corresponding reduced initial cost and upkeep expense. It has apparently been the general sentiment that further steps in this direction were impossible without sacrificing fuel economy and engine performance, for no practical models which truly combine these three features have appeared in use.

Presently used commercial carburetors are complicated by the presence of fuel reservoirs or float chambers which require an altogether unrealistic complexity of the body structure or 40 casting, not to mention the presence of temperamental float valves which can cause severe fire hazards by their failure to operate freely. Further complications introducing initial costs as well as upkeep expenses include accelerating 45 pumps and wells, plural venturis, controllable mixture altering means such as strangler or choke valves, automatic controls for such choke valves, and automatic air valves with or without interconnected fuel metering controls.

It is an object of the invention to provide a carburetor which can be operated in conjunction with the conventional fuel pump, but which is at the same time proof against pressure ejection 55 of fuel due to sticking float valves, and hence

2

against the severe fire hazard occasioned thereby.

It is another object of the invention to provide a carburetor which takes full advantage of modern fuel pump characteristics and which relies in part on fuel pump pressure both as an atomizing factor for the liquid fuel and as a fuel control agent capable of largely displacing the usual air-speed responsive fluid emission nozzle with its attendant mixture compensation problems.

It is another purpose of this invention to provide a carburetor suitable for conventional stock motor vehicles which reduces the mixing of fuel and air to its simplest terms whereby to reduce both initial cost and maintenance expense of the carburetor, but which at the same time maintains modern standards of performance with regard to reliable starting and idling, smooth acceleration and high power at full throttle.

A further object of the invention is the effecting of marked improvement of carburetion in the direction of fuel economy, as compared with present stock carburetors, and the attainment of this end in concert with the satisfaction of the above-mentioned purpose relating to simplicity and performance.

In carrying out my invention I have devised a fuel-air mixing device or carburetor which can be constructed using a single individual body or casting of relatively simple outline which can be prepared for use by a plurality of straight drilled passages, and plugs and inserts therefor.

It is another object of the invention to provide a carburetor in which the fuel induction jet or jets communicate with an auxiliary air passage where fluid fuel from the jets under fuel pump pressure is atomized to form a rich mixture with a portion of the air prior to its introduction into the main air stream, a portion of said air passage forming a nonrestrictive deflecting nozzle for introduction of the premix into the main air stream while substantially completing the atomization of the fuel.

It is still another object of the invention to provide a carburetor in which the moving operating parts consist essentially of a throttle valve and a main jet metering rod mechanically interconnected; but wherein the proper conditions for starting, running at all ordinary speeds, accelerating, and high power or speed can still be furnished with reasonable accuracy and at substantial economy over presently used types of carburetors.

Another object of this invention is the provision of a carburetor which provides reliable

starting performance and still avoids the use of a strangler or choke valve and automatic controls, and hence eliminates the attendant disadvantages.

Still another object of the invention is the provision of an arrangement of air passages such that a metering of the fluid inlet in consonance with the throttle movement is all that is necessary to provide adequate mixture control under all conditions.

A further object of the invention is the provision of an air inlet for the auxiliary air passage so arranged as to draw its air from a source protected by the conventional air filter, and to tap the main air stream in such a way as to measure its velocity and proportion the air velocity in the auxiliary air path thereto.

A further object of the invention is the provision of a parallel arrangement of a main jet and an idling jet so that the fuel issuing from either or both will pass into an auxiliary air current in atomized form prior to the admission of such current to the main air stream.

Another object of the invention is the provision of a carburetor in which the main fuel induction nozzle which introduces the fuel mixture into the main air stream is a conduit intermediate apertured for fuel escape and in which one end is connected to the auxiliary air passage and the other end communicates with an area of variable reduced pressure at the manifold side of the throttle valve.

Another object of the invention is the provision of a carburetor in which the introduction of fuel into the air stream can be effected without the necessity for severe restriction therein, such as venturis and the like which limit the power output of the engine.

A still further object of the invention is the provision of a carburetor having any or all of the foregoing features and advantages, and in which the average fuel consumption for a given automobile under comparable conditions and for all ordinary types of operation can be reduced at least twenty percent on the basis of the fuel consumed using a stock carburetor of the float chamber, plural jet, accelerator pump type currently in use and in prime operating condition, and using equivalent performance adjustments for both types.

Additional features and advantages will herein-after appear.

In the drawings:

Figure 1 is a front elevation of the carburetor of this invention.

Fig. 2 is a side elevation of the device of Fig. 1 taken from the right hand side and looking towards the left.

Fig. 3 is a section taken on line 3—3 of Fig. 2.

Fig. 4 is a section taken on line 4—4 of Figs. 1 and 3.

Fig. 5 is a detailed section taken on line 5—5 of Fig. 1 and 3.

Figs. 6, 7 and 8 are elevations of interchangeable metering members usable with the carburetors of Figs. 1 to 5 and illustrating several different suitable profiles.

Fig. 9 is a partial section similar to Fig. 4, but illustrating a modified form of the mechanical interconnection between the throttle and the fuel metering means.

The carburetor of this invention comprises a body member 10 which is preferably a single, integral casting. A large passage 12 running through the center of the body 10 constitutes

the main air duct and mixing chamber. The upper end of the body 10 is provided with means such as the seat 14 for receiving the collar 16 of a conventional air filter. The lower end of the body 10 is shaped to provide a sealing flange 18 which is bolted to a corresponding flange 20 on the intake manifold. On one side of the body 10 is an integral enlargement or boss 22 which, together with another integral boss 24 on the opposite side, provides for most of the principal operating parts and connections to the carburetor as will hereinafter appear. A small boss 26 near the lower end of the body 10 provides for the conventional vacuum connection 28 communicating with a port 29 opening in the air passage 12 for controlling the spark advancing and retarding mechanism.

Throttle valve assembly

20 The carburetor of this invention is essentially a posterior throttle carburetor, in that the throttle valve is located at a position in the main air stream, downstream from the fuel emission apparatus.

25 A horizontal bore 30 rotatably carries the throttle shaft 32 which extends diametrically of the bore 12 at the lower part thereof, and beyond each side of the casting, and has mounted thereon a butterfly valve 34 of the proper size and shape to open and close the main air passage 12. An enlarged bore 36 is formed in the lower end 38 of the boss 22 in line with the bore 30 to form a gear housing in a manner which will presently appear, and the same is closed 30 at its outer end by a combined cover plate and bushing member 40. Rotatably mounted on the end of the shaft 32 is a sleeve 42, one end of which is housed in the bore 36 and provided with spur gear teeth 44. The other end has 35 the configuration of a worm wheel 46 and extends through and outside the cover plate 40. Surrounding the outer end of the shaft 32 as well as the sleeve 42 is the drive sleeve 48 integral with an operating lever 50 which is connected to a member 52 in the conventional throttle operating linkage (Fig. 2). Sleeve 48 is firmly attached to the end of shaft 32 by means of a set screw 54 and extends into the central opening of the bushing 40 to rotatably support the shaft 32 and the sleeve 42 therein. A worm or screw 56 40 is rotatably mounted in a socket 58 in the sleeve 48, meshes with the worm wheel 46 on sleeve 42, and is provided with friction means 60 for retaining it in adjusted position. The angular relationship of the operating lever 50 and the attached throttle valve 34 to the spur gear 44 is 45 accordingly normally fixed, but it can be readily adjusted as desired by means of the worm and worm wheel connection 46, 56 for a purpose which will hereinafter appear. The other end of shaft 32 is received in a collar 62 which is fixed thereon by means of the set screw 64. The collar 62 50 also carries an arm 66 in which is threadedly received the stop screw 68 arranged to engage a surface of the boss 24 to prevent the valve 34 from closing altogether and for adjusting the size of such minimum opening. The arm 66 is 55 preferably split and sprung so as to frictionally retain the screw 68 against inadvertent rotation due to vibration and the like. Arm 66 also 60 includes a stop surface 67 which cooperates with a portion of the boss 24 to prevent opening of the throttle 34 beyond full open position.

Auxiliary air path

75 Another substantially diametric bore 70 crosses

the throat of the main air passage 12 and is formed in the upper portion 72 of the boss 22 as well as the upper portion of the boss 24. A nozzle tube 74 with orifices 76 in the bottom thereof is inserted from the open end of the bore in boss 24, which is then closed with a screw cap 78. Preferably there are several orifices 76 of such size as to total approximately the internal cross section of the tube 74. A smaller port 80 is drilled in the upper portion 72 of boss 22 in alignment with the central opening of the tube 74, and its outer end is closed by a plug 82. A plugged horizontal bore 84 communicates with the bore 80 and with an upwardly sloping bore 86 which opens on the interior of the main air passage 12 in the boss 88 integrally formed therein. Firmly fastened in the boss 88 and extending upwardly therefrom is a funnel-shaped air admittance member or air scoop 90 which projects into and parallels approximately the direction of air flow in the main air path, opening in a direction opposite to that of the air flow.

It will be seen that a series of openings or passages including the interior of the air scoop 90, the bore 86, the bore 84, the bore 80, the interior of tube 74 and nozzle openings 76, provide an auxiliary or secondary air path through which a portion of the air which would normally follow the main air passage is detoured.

Flatspot Control Passage

An additional passage, for modifying somewhat the flow in the auxiliary air path in a manner hereinafter described, consists of a vertical bore 94 in the boss 24, communicating with a horizontal bore 96 and the communicating, plugged, upwardly sloping bore 98, the bore 96 opening upon the main air stream at a port 100 located at the other side of the throttle valve 34 from the nozzle tube 74, and the bore 98 opening through the screw cap 78 into the interior of tube 74.

Main fuel jet, metering assembly, and throttle interconnection

A vertical bore 102 starts at the top of boss 22 and communicates with the enlarged bore or gear housing 36 and with the reduced bore 80 of the auxiliary air path. A guide block 104 is press-fitted in the bore 102 below the reduced bore 80, and the same snugly but slidably receives an operating pin 106. Also located in the bore 102 just above the intersecting reduced bore 80 is a press-fitted fuel jet insert 108. A bore 110 (Fig. 4) in the upper part of the boss 72 intersects the bore 102 just above the jet insert 108 and is provided with a fitting 112 for connection to the fuel line 114 which leads to the conventional fuel pump (not shown). A bore 115 connects the bottom of the gear housing 36 with the air passage 12 to drain off any leakage fuel from the housing 36. The upper end of the bore 102 is enlarged and tapped to receive cap screw 116 which closes the upper end of the bore 102 and retains the upper end of a coil spring 118, the lower end of which presses against the urging downwardly a plug 120 which fills the bore 102 and is slidably therein. The plug 120 has an integral depending projection 122 which passes through and normally seats in the orifice of jet 108. The projection 122 includes the base portion 122a of moderate taper and a nose 122b of increased taper for a purpose which will be more fully described hereinafter. The lower end of the nose 122b is flat or otherwise designed for

engagement with the upper end of the operating pin 106. A bore 124 parallel to and offset from the bore 102 opens at the bottom of the lower section 38 of the boss 22 and is closed by a screw plug 126. The bore 124 communicates with the gear housing 36, and by a slot 128 with the bore 102. Slidably mounted in the bore 124 is a rack member 130 the toothed portion of which is meshed with the spur gear 44. The upper end of the rack member 130 carries a lateral projection 132 which passes through slot 128 and underlies the lower end of the operating rod 106 in position to actuate the same. It will be seen that rotation of the shaft 32 to produce opening movement of the throttle butterfly 34, i.e. a counter-clockwise rotation as shown in Fig. 4, will raise the rack member 130 and with it the operating pin 106 to thereby lift the metering projection 122 and provide a slowly but progressively enlarging annular orifice between the jet and the metering projection. Clockwise rotation of the shaft 32 retracts the rack 130 and allows spring 118 to depress the metering member 120, 122 and operating pin 106 and ultimately to return them to the position shown in Fig. 4. It should also be noted that the parts of boss 22 may be so arranged, if desired, that bore 102 is in line with bore 124, whereupon lateral projection 132 would be dispensed with and operating rod 106 could either rest directly on or be integral with rack member 130. The series of elements just described, including spur gear 44, rack 130, operating pin 106 and metering member 122 provide for mechanical interconnection between the throttle valve and the main fuel jet orifice for a purpose to be more fully described hereinafter.

Idling jet

The idling fuel supply is provided by a compound bore 134 which intersects the bore 102 just above the main jet insert 108, and a vertical bore 136 which intersects both the bores 134 and 80 and is closed at its upper end by a plug 138. Bores 134 and 136 accordingly constitute a fuel bypass around the main jet 108. A step 140 in the bore 134 constitutes a valve seat or jet, the orifice opening of which is controlled by a needle valve 142. The needle valve 142 is integral with a screw 144 which is threaded into the outer end of the bore 134 and retained in adjusted position by the usual friction spring 146.

Connection and adjustment

The carburetor is installed and connected as shown with the air filter collar 16, the intake manifold flange 20, the fuel pump output line 114, and the suction line 28 to the spark advance mechanism, whereupon the device is in condition to be adjusted and used. The adjustments necessary consist merely of the main mixture setting and the idling speed.

The screw 144, which appears at first glance to adjust the idling mixture, is in fact a fixed adjustment and is seldom if ever touched. Under the fuel pump pressures normally used the discharge of fuel from the orifice of valve 140, 142 is quite sufficient for idling when this orifice is extremely small and when the screw 144 appears to be tight down on its seat 140 as shown in Fig. 3. This screw construction is used as the most expedient and simplest means for obtaining an exceedingly minute orifice which can also be adjusted when necessary. Once a proper value for the idler jet orifice setting for a given set of conditions (particularly for a given fuel pump

pressure and motor displacement) has been determined by experiment and road test, the same is readily duplicated as follows. The maximum vacuum which can be pulled by a small vacuum pump or air exhausting mechanism is determined, and the drop in said maximum vacuum which the test orifice produces when connected to the intake of the exhausting mechanism is noted. Orifices on other carburetors can be similarly set with great accuracy, then, by merely connecting them to the intake of the same or a similar air exhausting device and adjusting the orifice to reduce the maximum vacuum by the same amount. If desired, means for locking or sealing this adjustment, once made, can be provided.

In order to adjust the carburetor all that is required is that the idling speed adjustment screw 68 be set up a few turns to insure that the throttle 34 has a substantial opening, that the engine will turn over with moderate speed, and that the operating rod 106 has some substantial lifting effect on the metering projection 122 to open the main orifice at jet 108 a significant amount. It is then merely a matter of experimenting with the screw or worm 56, which is capable of producing a very slow adjustment in response to large operating movements, until the engine turns over most rapidly for the given throttle setting as already determined by screw 68. This adjustment of worm 56 produces the proper orifice at the main fuel jet as determined by the annular space between jet 108 and metering projection 122, to correspond with the predetermined opening of throttle valve 34. It likewise produces correspondingly proper orifice openings for all other conditions of running and openings of the throttle valve 34 provided the metering projection 122 is suitably configured in accordance with principles which are set down hereinafter. This adjustment of screw 56, is, of course, maintained by virtue of its coaction with worm wheel 46 and friction means 60. Once an accurate mixture setting is thus obtained, the idling speed adjustment screw 68 is merely returned to a position wherein the idling speed has any appropriate or desired value. With these two basic adjustments properly made, the carburetor of this invention will be found to operate properly over the full normal range of operating conditions.

Operation—in general

As in most plain tube carburetors there is an air flow in the direction of arrow A, Fig. 3, through passage 12 which flow is induced by the pumping action of the engine cylinders on intake stroke, and the speed for any given loading of this flow is roughly proportional to the engine speed. At the same time, in the carburetor of this invention, there is also produced a parallel or auxiliary air current through the passages 90, 86, 84, 80, 74, 76. This current is probably much reduced in speed by virtue of its tortuous and high friction path, but is also probably essentially proportional to the main air current A by reason of the position of the inlet funnel 90 which is so directed as to take an approximate reading of the velocity in the main air stream. The speed of the air current through the auxiliary path is, however, probably sufficiently reduced that the depression effect thereof on the liquid fuel jets 108 and 140 can be ignored, especially by comparison with the fuel ejective effect of the pressure due to the conventional fuel pump. This pressure is about 5 p. s. i. in most vehicles and is capable of being

very accurately predetermined and of remaining accurate over long periods of service in practically all modern fuel pumps. It is also contemplated that even better results than are described below herein will be obtained if, when the carburetor of this invention is installed, the usual fuel pump spring is replaced by one which increases the fuel pump pressure to a maximum safe value for the fuel system of the particular automobile in question, in order to take the fullest advantage of the benefits of the present invention. It is likewise probable that when use of the invention becomes general, fuel systems having slightly higher safe pressure values will also be installed to put the invention to its fullest use.

The liquid fuel under pump pressure, when forced through the tiny orifices at jet 108 or jet 140 or both, is thoroughly broken up into exceedingly minute droplets and reaches a high state of atomization in the auxiliary air current which retains for the most part its gaseous form and issues into the main air stream at ports 76. The fuel mixture while still in the auxiliary path is, of course, excessively rich, but when diluted by mixture with the main air current A, it assumes approximately the desired 15 to 1 ratio under most circumstances and is then readily usable by the engine. While, because of their size and number, no restriction in area occurs at the openings 76, it should be noted that the sudden deviation in path together with the break-up of the flow into a plurality of small streams results in the further and practically complete atomization of any possibly remaining droplets of liquid fuel. Also possibly contributing to this effect is the arrangement of the ports 76 at the underside of tube 14, in a low pressure zone created by the non-streamlined flow about the circular cross section of the tube. This instantaneous reduced pressure probably insures a high vaporization rate of any tiny liquid fuel particles which might remain suspended in the stream.

From the foregoing description it can be seen that since the rate of fuel emission from the jets is not under the control of the air stream as in the ordinary suction nozzle carburetor, provision must be made for increasing fuel flow as the main air stream A increases in speed. This speed-up of both air streams occurs in response to increased speed of the engine which is brought about by opening the throttle valve 34 as in the ordinary carburetor. Enlargement of the orifice between jet 108 and metering projection 122 occurs in concert with the opening of throttle valve 34 which controls the air flow due to its interconnection therewith by sleeve 48, worm 56, sleeve 42 including worm wheel 46 and gear 44, rack member 130, 132 and operating rod 106. The orifice 108, 122 consequently sprays more liquid fuel under fuel pump pressure into the auxiliary air stream. Since the auxiliary air stream is traveling at a proportionately faster rate as determined by the speed of the main air stream, its mixture value remains about the same, and the final mixture with the main air stream also retains its designated fuel-air ratio. The foregoing remarks, of course, apply to a deliberate advance in throttle opening where no sudden changes are involved and running mixtures are called for rather than maximum power.

Acceleration

When we modify the preceding state of facts to the extent of opening the throttle rapidly with the intent of developing smooth, quick accelera-

tion of the engine, a different state of affairs is observed. A lively throttle opening normally does not cause immediate increase in air velocity because time is required for the engine to receive its added charge and to speed up. At ordinary full economy mixture and under load this speed-up can only take place rather slowly, so that a full power mixture, substantially richer than ordinary, is required during the accelerating interval for satisfactory performance in this respect. Whereas this exigency is taken care of by automatic pumps or self-emptying wells in the usual carburetor, no such expensive complication of the structure is found necessary in the device of this invention. It will be noted that a wide-open position of throttle 34 also opens the main jet orifice 108, 122 to its fullest extent. Inasmuch as neither air path has as yet been speeded up, the fuel ejected is much higher in proportion to the air than ordinarily so that the auxiliary air path mixture and the final mixture are both enriched substantially beyond normal condition and hence give full power and smooth acceleration performance. Furthermore, the degree of this enrichment, is proportioned almost exactly to the difference between present speed and the terminal speed corresponding to the throttle opening so that the enriching effect is promptly decreased as speed picks up and promptly terminated as desired velocity is reached giving just the expenditure of fuel needed for proper performance with none wasted in periods of rich mixture production when there is in fact no demand therefor.

Starting and idling

Difficulties with starting under ordinary carburetion, and attendant damaging effects on the engine can be laid directly at the door of the usual strangler or choke valve. Since the cranking speed of the engine is extremely slow, corresponding air speed in the usual carburetor throat is insufficient to draw off enough fluid fuel from the nozzle to bring the mixture ratio up to firing value, or at any rate, the fluid fuel in the air stream is so poorly broken up, due to low air speed and a cold manifold, that the effective mixture of the gaseous portion of the charge when it reaches the cylinder is significantly below combustible proportions. To correct this, it is almost universal to employ a choke or strangler valve which closes off or restricts the air stream ahead of the fuel nozzle and hence applies all or a portion of the static engine depression directly to the fuel jet to draw off a higher proportion of liquid fuel. With more droplets present to vaporize, the truly gaseous portion of the mixture can be brought up to combustion value, although the actual weight ratio of the fuel present to the air present is much higher than the appropriate 1 to 15. This is manifestly a wasteful procedure, but can be tolerated if the choke adjustment is properly tended and the choke valve opened when no longer needed. Since the manual adjustment is ticklish and bothersome, it is simpler for the operator to leave it rich long after it is needed, with consequent fuel waste, washing down of cylinder wall lubricant, and dangerous dilution of the crank case contents. Most modern carburetors attempt to avoid this waste and potential engine damage by encumbering the choke valve with superimposed automatic controls which frequently give trouble and fail to function properly. The foregoing waste, damage and inconvenience is obviated by the

present invention wherein no choke valve at all is present and none is needed. Starting position of the carburetor is merely that in which the throttle valve 34 is closed as far as possible with stop screw 68 against the boss 24. Under these circumstances the main jet 108, 122 is closed and little if any fuel is allowed to pass therethrough even under fuel pump pressure. In this connection it should be noted that the spring pressure of spring 118, even though not particularly heavy, is sufficient to substantially seal the opening in jet 108 due to the very small taper of the sealing portion of the metering projection 122. Fuel induction, therefore, is effected mainly through the exceedingly minute orifice at the idling jet 140. (While it is conceivable that idling jet 140 could be dispensed with and means provided for adjusting the minimum opening of jet 108 as a substitute therefor, the structure shown is regarded as more practical in many respects, and is described in detail as the preferred form.) Normally the setting of this orifice between jet 140 and needle valve 142 is such as to cause a mixture just equal to or slightly richer than the most economical setting possible for the air speeds involved at idling speed of the engine. When the engine is to be started, of course, the cranking speed and induced air speeds in the main and auxiliary air paths are substantially less than at idling speed so that, assuming full fuel pump pressure, the mixture fed to the cylinders would be much richer than the ordinary economical mixture. There may be certain tendencies such as pulsating of the fuel pump at slow engine speeds, or an instantaneous lag in fuel pump pressure build-up which would reduce fuel output at the jet 140 for just a moment, whereby the mixture would be leaned to ideal combustion proportions but whether this occurs or not the range of mixtures which the jet 140 causes to exist in the intake manifold is never such as to prevent firing of the engine, for initial firing can occur very readily over a wide range of mixtures from just slightly leaner than ideal running mixture to quite rich. Once the engine has caught, the mixture present is instantaneously adjusted to proper idling value by the pick-up in air speed through both air paths, which finally steadies down at the speed for which the output of the orifice at jet 140 is accurately set, and the mixture is thereafter automatically taken care of without attention by the operator and without any of the complicated controls normally considered desirable for the starting operation. Since mixture control is instantaneous once the engine is started it will be seen that there is no fuel waste due to the long period of operation at a rich mixture setting which so often occurs with the conventional manual choke. Furthermore the full atomizing effect of the pump pressure at jet 140, together with the break-up and deflection of the auxiliary air current at orifices 16 brings about substantially complete subdivision of the fluid fuel, as in ordinary running, in spite of the relatively slow air speed through the carburetor under cranking and idling conditions. For this reason the danger, ever-present in conventional carburetors of flooding the engine with fluid fuel droplets which so enrich subsequent charges as to prevent starting is practically obviated. Likewise danger to cylinder walls and crank case lubricant due to the cleaning and thinning effects of the fuel when in fluid form is almost entirely avoided. It should also be noted that the degree of atomi-

zation which the carburetor of the present invention effects is such that the temperature of the intake manifold loses much of its significance with respect to starting, and the engine will idle properly immediately after starting cold due to the fact that the weight of fuel employed is taken full advantage of. Another way of expressing this same condition is to state that the apparent mixture (overall weight of fuel to overall weight of air) is substantially equal to the effective mixture (the ratio of the weights on the basis of the part of the fuel which is in substantially gaseous state and hence usable). Thus the necessity for the operator to tend the apparent mixture by a choke or strangler valve, or the necessity for complicated automatic controls governing the apparent mixture during warm-up idling is obviated.

Flatspot correction

In the development of the carburetor of the present invention it was found that with the structure substantially as illustrated in the drawings, but lacking the conduit 98, 94, 96, substantially all of the foregoing features of operation were present. The only readily detectable difference from the model as shown in the drawing was that the response to accelerator operation was sluggish and unfavorable at a medium throttle setting corresponding to a car speed of about 30 M. P. H., but was proper at all other speeds. Even then this flatspot could be adjusted out by a resetting of the mixture control screw 56, but with some slight reduction in fuel economy at other speeds. Certain conditions existing in the ordinary suction nozzle carburetor wherein there is usually a transfer of the fuel emission from a pilot jet operated either by static engine depression or by air flow at the edge of the throttle, which drops off from maximum to zero, to a main jet operated by kinetic depression due to air flow past the nozzle which picks up from zero and increases to a maximum, are usually considered to be responsible for a flatspot when the pilot operation is not sufficiently extended, the main jet is too long in coming fully into action, or both. Since the only structure corresponding to a pilot jet in the present device, namely idling jet 140, 142 is fully operative at all times, no similar cause for the flatspot obtains.

One theory which has been advanced and which appears to provide a possible explanation for the flatspot is that the geometry of the auxiliary air path 90, 86, 84, 80, 74, 76 is such that a certain air speed within the range of air speeds employed sets up a material vibration of the air column in said path, or some significant portion thereof. This vibration may have limited the flow through the auxiliary path and prevented its bearing the proper relation to the main air stream flow, thus temporarily leaning the mixture to a degree unsuitable for brisk performance.

Whatever the cause of this phenomenon, it was found that by merely providing a constricted passage connecting the end of nozzle tube 74 with the main air stream at a point which lies at the other side of the throttle valve 34, the conditions were sufficiently changed to correct the flatspot condition described even using the mixture adjustment of screw 56 which is the best for economy in all ranges. As previously described the flatspot correcting conduit consists of the passage 98, 94, 96 and is of materially reduced cross section so that little if any of the fuel mixture ever reaches the main air stream by

way of orifice 100 even when the throttle is in idling position, and its function appears to be merely to correct the condition which produced the impedance in the auxiliary air path resulting in the flatspot, possibly by so changing the geometry of the auxiliary air path that the vibratory response if any is displaced to an air speed outside of the range employed. Other forms of the flatspot correction conduit are also suitable and it has been found, for example, that a small readily bendable tube of copper or the like attached to the body 10 by the usual tube fittings may be conveniently and successfully used in place of the passage consisting of drill holes 98, 94, 96 in the boss 24.

Economy of operation

Tests have been run by operating the same automobile with conventional stock carburetors in good condition, and then with the carburetor of this invention. Where the maximum efficiency attainable with the particular vehicle selected was found to be 18 miles per gallon with the stock carburetor during any extended period of running under average conditions, the best efficiency attainable with the carburetor of this invention on the same vehicle for a similar period of average operation has been found to be 26 miles per gallon, and in no case has the efficiency been found to drop below 22.75 miles per gallon for any extended period of running even though some severe upgrade tests may have been included therein. From the foregoing figures it can be readily calculated that the fuel saving effected is 20% at the minimum and would normally be significantly more, up to 30% being possible, and 25% being a safe average.

Adaptability to varying applications

It has been found that the carburetor of this invention is extremely adaptable with very minor revision. The only alteration necessary to provide for use with different types of engines, or to modify the economy-performance relationship in most respects is a tailoring of the metering projection of the metering member to suit particular conditions. In fact a wide variety of such metering members may be made in quantity and carried in stock for experimental purposes, since the same are readily replaced by anyone capable of removing the cap screw 116.

In Figs. 6 to 8 are shown three types of metering members illustrating the manner in which the contour may be altered to provide for various conditions. Fig. 6 is merely the member 120, 122 which is shown in Figs. 3 and 4. This member is designed to give fuel economy within the range stated above, and which provides for the best average type of performance with top vehicle speed and best full power mixture at full throttle due to the second slightly sharper tapered tip portion 122b. Fig. 7 represents a simple metering member 120, 122' wherein the metering projection 122' has a single taper of about 1° (similar to the taper of portion 122a in Fig. 6). This member gives slightly reduced top speed and slightly reduced power at full throttle as compared with the member of Fig. 6, and provides for a moderate increase in fuel economy. Fig. 8 shows the general contour of a metering member 120, 122" in which the metering member has a form of particular value in connection with a fuel pump pressure lower than average, e. g. about 2 p. s. i. While the fuel pressure will normally be adjusted rather than the metering projection

changed, the pressure being preferably 5 p. s. i. or higher, the structure in Fig. 8 serves to illustrate how this factor may be readily compensated for if necessary. The projection 122, in addition to a regular taper, has a slight flare at the top of its operating portion which causes the initial orifice opening to increase rapidly which compensates for the decreased fuel impetus produced by the fuel pump. Other metering members, not shown, may be made using slightly different tapers for use with engines having different displacements, and still other metering members may be specially devised having even more complex contours if desired to produce desired changes in performance or economy over any portion of the operating range.

Fig. 9 illustrates a slightly modified form of the invention wherein all parts which are the same as in previous views bear the same reference characters and those which have correspondence to previously described parts bear the same reference characters primed. The body 10' and boss 22' are slightly modified in that no provision for the rack 130 is required at one side of the throttle shaft 32. The sleeve 42 has been replaced by a sleeve 42' which is the same except for having the cam 44' in place of gear 44. A follower 130' slides in bore 102', rests on the cam 44' and receives upon its upper surface the thrust of operating rod 106. The cam 44' shown in Fig. 9 is a straight line cam giving a fixed rise per degree rotation of the shaft 32, and the operation of the device is in all respects the same as the device of Figs. 3 and 4. While tailoring of the surface of cam 44' is a possible method for modifying the operation of the carburetor, it is not preferred since the use of interchangeable metering members, or the preparation of any special contour of metering member as previously described is much less costly, more expedient and accurate and is consequently the form at present preferred.

From the foregoing description it can be seen that this invention provides a carburetor of exceedingly simplified construction and which, due to the particular features above pointed out, is capable of directly using and applying fuel pump pressures to the carburetion of the fluid fuel, whereby improved performance characteristics together with markedly increased economy are achieved.

Variations and modifications may be made within the scope of the claims and portions of the improvements may be used without others.

I claim:

1. A carburetor comprising means providing a main air supply path for connection with the intake manifold of an internal combustion engine; additional means providing an auxiliary air path connected in parallel with said main path, said additional means including an air scoop extending into said main air path and opening in a direction opposite to the normal direction of air flow therein, and a tube extending across said main air path and having a plurality of apertures formed therein; two fuel emission orifices, one of which is variable, opening on said auxiliary air path; means for supplying liquid fuel under pressure in excess of atmospheric to said orifices; a movable throttle valve for controlling the flow in said main air path; and means for varying the size of said variable orifice in accordance with the position of said throttle valve including means for adjusting the relationship of the orifice size to the throttle position.

2. A carburetor comprising a tubular shell having a flange at one end for connection to the intake manifold of an internal combustion engine; an integral boss on the outside of said shell; a throttle valve for opening and closing said tube near one end and having an operating shaft mounted for rotation on said shell, said boss being apertured to receive one end of said shaft; a nozzle member mounted in said boss and extending into the interior of the shell at an intermediate point in its length; an air scoop extending from said boss interiorly of said shell near the other end thereof and in a direction opening away from said throttle valve, said boss being provided with an air passage connecting said air scoop and said nozzle; means on said boss for making connection with the output line of a conventional motor vehicle fuel pump, said boss having formed therein a fuel passage connecting said pump connection means directly with said air passage; means carried by said boss for variably restricting said fuel passage; and means carried by said boss and mechanically connected with said shaft for controlling the operation of said restricting means as an incident to movement of said throttle valve.

3. A carburetor comprising a tubular shell having a flange at one end for connection to the intake manifold of an internal combustion engine; an integral boss on the outside of said shell; a throttle valve for opening and closing said tube near one end and having an operating shaft mounted for rotation on said shell, said boss being apertured to receive one end of said shaft; a nozzle member mounted in said boss and extending into the interior of the shell at an intermediate point in its length; an air scoop extending from said boss interiorly of said shell near the other end thereof and in a direction opening away from said throttle valve, said boss being provided with an air passage connecting said air scoop and said nozzle; means on said boss for making connection with the output line of a conventional motor vehicle fuel pump, said boss having formed therein a fuel duct leading from said pump connection means, and having a straight bore intersecting said fuel duct, said air passage and said shaft receiving an aperture; a fuel jet in said bore between the fuel duct and the air passage; a metering element slidable in said bore and having a projection cooperating with said jet for providing a variable orifice; and operating means slidable in said bore, in contact with said metering element and actuated by mechanism on said shaft for enlarging and restricting said orifice in response to rotation of said shaft.

4. A carburetor comprising a tubular shell having a flange at one end for connection to the intake manifold of an internal combustion engine; an integral boss on the outside of said shell; a throttle valve for opening and closing said tube near one end and having an operating shaft mounted for rotation on said shell, said boss being apertured to receive one end of said shaft; a tubular nozzle member mounted at one end in said boss and extending across the shell at an intermediate point in its length; conduit means connecting the other end of said nozzle member with the interior of the shell at the end beyond said throttle valve; an air scoop extending from said boss interiorly of said shell near the other end thereof and in a direction opening away from said throttle valve, said boss being provided with an air passage connecting said air scoop and said one end of the nozzle; means on said boss for

making connection with the output line of a conventional motor vehicle fuel pump, said boss having formed therein a fuel passage connecting said pump connection means directly with said air passage; means carried by said boss for variably restricting said fuel passage; and means carried by said boss and mechanically connected with said shaft for controlling the operation of said restricting means as an incident to movement of said throttle valve.

5. A carburetor comprising a tubular shell having a flange at one end for connection to the intake manifold of an internal combustion engine; an integral boss on the outside of said shell; a throttle valve for opening and closing said tube near one end and having an operating shaft mounted for rotation on said shell, said boss being apertured to receive one end of said shaft; a tubular nozzle member mounted at one end in said boss and extending across the shell at an intermediate point in its length; conduit means connecting the other end of said nozzle member with the interior of the shell at the end beyond said throttle valve; an air scoop extending from said boss interiorly of said shell near the other end thereof and in a direction opening away from said throttle valve, said boss being provided with an air passage connecting said air scoop and said one end of the nozzle; means on said boss for making connection with the output line of a conventional motor vehicle fuel pump, said boss having formed therein a fuel duct leading from said pump connection means, and having a straight bore intersecting said fuel duct, said air passage and said shaft receiving aperture; a fuel jet in said bore between the fuel duct and the air passage; a metering element slidable in said bore and having a projection cooperating with said jet for providing a variable orifice; and operating means slidable in said bore, in contact with said metering element and actuated by mechanism on said shaft for enlarging and restricting said orifice in response to rotation of said shaft.

6. In a carburetor, means providing a main air supply path for connection to the intake manifold of an internal combustion engine; moderately restricted conduit means connected at two points with said main path and constituting means for providing a parallel auxiliary air path between two locations in said main air path; a throttle valve for controlling the flow in said main air path, located therein to one side of said auxiliary air path; highly restricted conduit means connected between that portion of the auxiliary air path from which air is returned to the main air path, and the main air path at the other side of said throttle valve from said auxiliary air path; and means for discharging liquid fuel under pressure in excess of atmospheric into the air flowing in said auxiliary air path.

7. In a carburetor, a tubular shell; a small laterally apertured tube extending transversely across said shell; a throttle valve for opening and closing the passage in said shell at one side of said tube; an air scoop entering the passage in said shell on the same side of the throttle valve as said tube with its opening directed away from said throttle valve; conduit means connecting said air scoop with one end of said apertured tube thus constituting means for providing a parallel auxiliary air path between two locations in said shell; restricted conduit means connected to the other end of said tube and to the interior of said shell at a point located on the other side of said throttle from said apertured tube; and means for discharging liquid fuel under pressure in excess of atmospheric into the air flowing in said auxiliary air path.

8. In a posterior throttle carburetor, a frame 20 providing an air passage, a jet on said frame opening on said air passage for admitting fluid fuel under pressure into said air passage; a metering element disposed in said jet and slidable therein for varying the effective orifice thereof; a 25 throttle valve shaft rotatable on said frame; means connecting said throttle shaft with said metering member for controlling the position thereof in accordance with the rotative position of said throttle shaft; and a readily accessible 30 adjustable connection between said shaft and said means for adjusting the effective orifice of said jet with respect to a given position of said throttle shaft, said adjustable connection comprising a worm rotatably connected with said shaft, and a 35 worm wheel mounted concentrically on said shaft in engagement with said worm and incapable of rotation with respect to said shaft except in response to rotation of said worm.
